UNITED STATES PATENT OFFICE

162,370

SURVEYING INSTRUMENT

Allister L. Baker, Jersey City, N. J., assignor to
Keuffel & Esser Company, Hoboken, N. J., a cor-
poration of New Jersey

Application October 6, 1948, Serial No. 148,987

Term of patent 14 years

(Cl. D52—1)

To all whom it may concern:

Be it known that I, Allister L. Baker, a citizen of the United States, residing at Jersey City in the county of Hudson and State of New Jersey, have invented a new, original, and ornamental Design for a Surveying Instrument, of which the following is a specification, reference being had to the accompanying drawing, forming part thereof.

Fig. 1 is a view in front elevation of a surveying instrument, showing my new design with a suitable leveling head which does not form part of the invention shown in dotted lines for illustrative purposes only.

Fig. 2 is a view in side elevation of the instrument as shown in Figure 1.

Fig. 3 is a view in plan of the instrument as shown in Figures 1 and 2.

I claim:

The ornamental design for a surveying instru-
ment, substantially as shown and described.

ALLISTER L. BAKER.
